UNITED STATES PATENT OFFICE.

BASIL G. AUSTIN, OF HARTFORD, CONNECTICUT, ASSIGNOR TO AUSTIN ORGAN COMPANY, OF HARTFORD, CONNECTICUT, A CORPORATION OF MAINE.

ELECTROPNEUMATIC ORGAN-ACTION.

1,335,417.

Specification of Letters Patent. Patented Mar. 30, 1920.

Original application filed May 29, 1916, Serial No. 100,502. Divided and this application filed January 2, 1918. Serial No. 209,981.

To all whom it may concern:

Be it known that I, BASIL G. AUSTIN, a citizen of the United States, residing at Hartford, in the county of Hartford and 5 State of Connecticut, have invented certain new and useful Improvements in Electropneumatic Organ-Action, of which the following is a specification.

This invention relates to electropneumatic 10 organ action, and among the objects of the invention is the provision of a valve structure which is simple and effective.

In the drawings accompanying and forming part of the present specification I have 15 shown a convenient form of embodiment of the invention which I will set forth fully in the following description. I do not, however, restrict myself to this disclosure; I may depart therefrom in several respects 20 within the scope of the invention defined by the claim following said description.

Referring to said drawings:

Figure 1 is a transverse section of an organ action involving the invention.

Fig. 2 is an enlarged sectional view of the magnet-operated valve and its adjuncts.

Fig. 3 is an inside face view of the casing for the magnet operated valve, and

Fig. 4 is an outside face view of the cage 30 for the pneumatically operated valve.

Like characters refer to like parts throughout the several views.

The structure involves relay mechanism comprising a main support as 2 and an auxiliary support as 3. Both these may as usual be of wood. The main support 2 has certain windways, hereinafter described, while the auxiliary support 3 constitutes what is known as a "relay bar." The two

40 parts 2 and 3 are connected by parts as 4 having windways as 5. The part 3 can be held to the part 2, and the connecting tubes 4 can be maintained in assembled relation with said parts 2 and 3 in some permanent

45 manner as by screws 6. The support or bar 3 carries a number of cases as 7 generally made of metal. A detailed description of one case and its accessories will, of course, apply to the others, and for this purpose reference may be had especially to Figs. 2 and 3. The case therein shown has on its inner side near the upper end thereof, the boss 8 adapted to snugly fit the passage 9, said case having near its lower end also on

the inner side the projection 10 to fit the 55 opening 11 in the relay bar 3. The case 7 is, therefore, removably mounted. It is held in position by a spring 12 connected with the relay bar 3 and bearing against the cap or cover member 13 as will hereinafter more 60 particularly appear. This cap or cover member 13 closes the outer open side of the case 7, fitting a rabbet therein, the packing 15 conveniently of paper, resting on the bottom of the rabbet. It will be understood 65 that the thin packing 15 has between its ends a slot 15' in constant register with both the ports 18 and 19. This cover piece 13 constitutes a supporting member for the magnet 16 of horse-shoe type, the poles of 70 the magnet being driven into holes in the said part 13. The free end of the spring 12 to which I have already referred is fitted in an indentation 17 in the cover piece 13. By disengaging the spring 12 from said part 13, 75 the latter can be dismounted as can also the case 7. In the cover piece 13 are ports 18 and 19. In the case 7 is an approximately oval flange 20, the space in which constitutes a port in register with the port 21 of the 80 relay bar 3, said port 21 being in communication with the atmosphere. Adapted to seat against the outer edge of the oval flange 20 is the valve 22 constituting an armature for the magnet 16 and faced on its 85 inner side as at 23 by leather or something of a similar soft nature. The parts 2 and 3 and their adjuncts hereinafter described are generally inclosed in a pressure box 2', the result being that when the magnet 16 is de- 90 energized, the pressure passing through the ports 18 and 19 closes the valve 22 against its seat as shown by full lines in Fig. 2.

The magnet 16 is normally deenergized. I have shown as connected with the terminals of the magnet the wires 25 and 26 constituting part of circuit connections which include a battery and a switch or other circuit closing device. When, however, it is energized by the operation of the switch, 95 push button or the like, the valve 22, constituting an armature for the magnet is attracted by the magnet or moved to the open or dotted line position in said Fig. 2. It will be noted that the valve 22 is off center 100 with respect to the magnet 16, the longitudinal axis of said magnet being as shown above the center of the valve, the result be-

ing that the valve is initially given a tip or swinging movement and is thereafter drawn straight outwardly, and owing to this particular relation the valve is more 5 efficiently and easily opened.

On the support or relay bar 3 is mounted a pneumatic 27 in communication with the port or passage 9 by way of the port 28. The movable member of the pneumatic is 10 connected with the stem 29 of the valve 30 mounted in the cage 31. This cage consists of a sheet metal shell covering the port or windway 32 leading from a pneumatic (not shown). The valve 30 controls the port 33 15 which it is shown as closing in Fig. 1. The cage or elongated shell 31 has in its outer side the port 34 from which the annular flange 35 extends inward the inner edge of said flange constituting a seat for the 20 valve 30. The port or windway 33 is in communication with atmosphere as is the port 36 into which the passage 5 hereinbefore described leads. The chamber 37 in the relay bar 3 with which the passage 25 or windway 5 communicates is also as will be obvious, in communication with the atmosphere. The shell 31 is merely fitted along the edge of its open side against the support 2; initially it may be held in position 30 by a small quantity of shellac placed along said edge, although this is not always necessary, because it can be removably held in place merely by the use of the spring 38 (or equivalent means) of bowed form, one 35 end of the spring being seated in the recess 39 in the upper edge of the relay bar 3, while the other end of the spring fits against the outer closed side of said cage or oblong shell 31. For holding the cage or shell 31 40 in proper relation, the pins 40 may be provided, these pins extending somewhat freely through perforations in the outer closed side of the cage and being driven into the support or bar 2. The spring 38 has an eye 45 at its inner end to fit over the upper of the two pins, by reason of which said upper pin aids in holding the spring in position. This provides an exceedingly simple way of holding the cage 31 in place. The use of 50 a valve as 30 and a valve as 22 and the hereinbefore described adjuncts thereof is in no sense new, the only novelty being in the manner in which the cage 31 is mounted, the way the spring 38 is associated with said 55 cage, and the novel relation between the valve 22 and its operating magnet 16 and certain details as will be more particularly set forth in my claim.

In Fig. 1 the parts are shown as occupying

their normal positions, the valve 30 being 60 closed against the inner end of the windway or port 33, while the valve 22 is closed against the port 20 as shown by full lines in Fig. 2. To obtain the pneumatic action as familiar in organs, the magnet 16 will be 65 energized to attract its armature 22 constituting a valve, so as to cover the ports 18 and 19 to pressure and put the pneumatic 70 27 into communication with the atmosphere. When this condition ensues, the pneumatic 75 or bellows 27 will be collapsed so that the valve 30 will be drawn away from the port 33 and cover the port 34, so that the windway 32 will be put into connection with the port 33 by way of the cage 31 to effect the 75 operation of the pneumatic or perform some equivalent act as quite common in organs.

When the magnet 16 is deenergized the valve 22 is moved by the pressure in the pressure box against its seat on the flange 80 20 as shown by full lines in Fig. 2, thus cutting off the bellows or pneumatic 27 from the atmosphere and admitting pressure, owing to which the pressure can force the valve 30 against its seat at the inner end of the 85 windway 33.

It will be noted that the side walls of the cage 31 and the pins 40 jointly act to guide the valve 30. It will also be noticed that the packing 15 is free or loose, by reason of 90 which it can be readily replaced if desired.

The present application is a division of an application filed by me May 29, 1916, Serial No. 100,502 which has issued as Patent No. 1,277,529 of Sept. 3, 1918, and to 95 which patent reference may be had for the construction of the action which involves the subject matter of the present application as well as that of the patent.

What I claim is:

A valve case having a port in communication with the atmosphere and provided with a cover having a port in communication with pressure, a valve normally held against the first mentioned port, a horseshoe magnet, the cover having perforations 105 into which the poles of the magnet are rigidly fitted, the center of the valve being at one side of the longitudinal axis of the magnet, and a packing between the valve 110 and the cover and free of them both.

In testimony whereof I affix my signature in the presence of two witnesses.

BASIL G. AUSTIN.

Witnesses:

JOHN T. AUSTIN,
HEATH SUTHERLAND.
